UNITED STATES PATENT OFFICE.

FRANK A. YOUNG, OF NEW YORK, N. Y., ASSIGNOR TO UNDERWOOD TYPEWRITER COMPANY, OF NEW YORK, N. Y., A CORPORATION OF DELAWARE.

TYPE-WRITING MACHINE.

1,044,331.

Specification of Letters Patent. Patented Nov. 12, 1912.

Application filed May 9, 1910. Serial No. 560,291.

To all whom it may concern:

Be it known that I, FRANK A. YOUNG, a citizen of the United States, residing in New York, in the county of New York and State of New York, have invented certain new and useful Improvements in Type-Writing Machines, of which the following is a specification.

My invention relates to a typewriting machine, the platen of which is shiftable between a normal or lower case printing position and an upper case printing position.

According to this invention, the platen in either position is locked rigidly to the carriage, against vibration or displacement therein.

The invention includes means independent of the carriage and platen frame, for determining and adjusting with exactness and certainty, the throw of the platen in the carriage.

A further feature of the invention is a means whereby the ribbon carrier is shifted and controlled in its movements from the platen shifting mechanism, to secure always a proper and true correlation of the two.

Other objects of the invention will be set forth in the following specification taken in connection with the accompanying drawings, in which:

Figure 1 is a view in perspective of the assembled mechanism, except for certain details omitted for the sake of clearness. Fig. 2 is a view of the mechanism in end elevation looking from the left hand side of the machine. Fig. 3 is a rear view. Fig. 4 is a view on the line 4-4 of Fig. 3, looking in the direction of the arrows. Fig. 5 is a view in front elevation of a portion of the left hand side of the mechanism, the keys and part of the platen frame being removed to show the mechanism to the rear thereof. Fig. 6 is a detail view in end elevation, of a portion of the key lever and eccentric shift mechanism, immediately operated thereby. Fig. 7 is a view in front elevation of the parts shown in Fig. 6. Fig. 8 is a view in side elevation of the eccentric for moving the platen. Fig. 9 is a view in front elevation of the parts shown in Fig. 8, partly in section. Fig. 10 is a detail side view, showing a part of the ribbon-vibrating mechanism.

Referring to the drawings, the carriage 1

is shown as mounted on the frame 2 of the machine to have longitudinal, but no other movement thereon. The carriage at its front, travels on the rail 3 fixed in the frame of the machine, and at its rear is attached by brackets 4 to a bar 5, which has longitudinal movement in the guideway 6 after a manner well known in the art. The platen 7 is supported at either end by bearings 8 on arms 9, hinged or pivoted to a rock-shaft 10 on the carriage. The platen frame 11 together with the platen and certain other parts, are all free to be shifted up and down with the arms 9, as the latter swing with the rock-shaft 10.

The platen frame and attached parts are shifted from upper to lower case position, and vice versa, with respect to type 40, by means of links or arms 12, pivoted at 13 to the platen frame, and their lower ends carried by eccentrics 14 on rock-shaft 15, (see Fig. 8), which latter has a bearing at either end on the carriage frame 1. With the eccentrics 14 in the position shown in the drawings, the platen is in lower case position. A turn of the eccentric shaft 180 degrees to the position shown in dotted lines in Figs. 8 and 9 causes the arms 12 to be lifted and brings the platen to upper case position. The movement of the eccentric shaft 15 is effected by shift keys 16 through the following mechanism.

The keys 16 are carried by bell crank levers 17 pivoted at 18, one to each side of the machine, in the usual manner. The rearmost arms of the levers 17 each carry a roller 19, which bears against one arm 20 of a lever 21, (see Figs. 6 and 7), fixed to a shaft 22 which rocks in the frame 2 of the machine. Springs 23 tend to hold the key levers 17 in normal or lower case position, and to return them to this position unless restrained from so doing. Springs 24 attached at 25 to the frame of the machine, and at 26, to arms 27 of the levers 21, serve to hold the lever arms 20 against the key levers 17, and to cause the levers 21 to follow the key levers as the latter return to lower case position. Fast to the shaft 22 is a rack 28 which meshes with a pinion 29 on the shaft 15, so that when the shaft 22 is rocked by the means described, the shaft 15 is also rocked, and the eccentrics 14 caused

to raise or lower the thrust rods 12 and the platen frame carried thereby. The shaft 15 is provided with a keyway 30 extending substantially the entire length thereof, which 5 engages a key on the pinion 29, whereby the shaft 15 is caused to turn with the pinion 29, but is free to move longitudinally with respect to the latter as the carriage is fed. Flanges 31 on the pinion 29 engage the rack 10 28 on either side, and cause the pinion to be held in mesh with the rack, regardless of the longitudinal movement of the carriage 1 and shaft 15.

The movement of the parts is such, that 15 eccentrics 14 are on dead center in both upper and lower case positions. When the eccentrics are on dead centers, they firmly support the platen frame on the carriage, and lock the two frames together. The key 20 levers 17 may be locked by any suitable means to hold the same depressed against the action of the springs 23 and 24. Such means for locking the key levers are well known in the art and are not shown in the 25 drawings. The throw of the key levers and of the levers 21 is determined by stops 32 adjustable in slots 33 in the arms 27 of levers 21. These stops on each depression of the 30 keys finally engage the key levers, as shown in dotted lines in Fig. 6, and bring the parts to rest. The key lever 17 engages the lever 21 on both sides of the pivot of the latter and further movement of either lever is thereby rendered impossible. The pivot or 35 shaft 22 lying midway of the stop 32 and roll 19, receives the shock as a direct blow and serves as a positive stop. The throw of the eccentric shaft 15 will be greater or less, according to the positions of stops 32. 40 In practice, the stops 32 are so adjusted, that the key levers and other parts come to rest when the eccentrics 14 are on dead center. The springs 24 are conveniently, although not necessarily, attached to the pins on 45 which the stops 32 are carried. The stops 32, the links and the eccentrics positively determine the upper case position of the platen frame.

The ribbon 41, through which the types 50 40 print, is threaded in the ribbon-carrier 42 (Fig. 10), which is vibrated up and down so as to maintain the ribbon adjacent the printing point in either the raised or lowered positions of the platen. Said ribbon-carrier is caused to shift up with the shifting 55 of the platen from lower to upper case position, or vice versa, by a rack or toothed segment 37 fast on the rocking shaft 22 (Figs. 1 and 2), in mesh with a rack 36 on 60 a bar 35 to raise and lower said bar as the shaft 22 is rocked in one direction or the other to raise or lower the platen. A ribbon-carrier lever 34 is fulcrumed at 43, upon 65 said bar 35, said lever being connected at 44, to the ribbon carrier 42 to transmit the

movement of the bar 35 thereto, to maintain the proper relation between the platen and ribbon at all times. A roller 37^a on the ribbon-carrier link is guided in an elongated bearing 38 constituting an actuator which vibrates the ribbon at the type strokes. Platen and ribbon-carrier preferably move approximately simultaneously in the same direction upon the rotation of the shaft 22. 70

The ribbon normally lies beneath the 75 printing point on the platen to render the writing visible. To cause the ribbon to cover the printing point at each type stroke, said bearing 38 is attached to the universal bar 45, which is caused to vibrate back and forth by the engagement of the type bars therewith as the types approach the platen, such vibration operating to rock the ribbon-carrier lever 34 on its pivot 43 to vibrate the ribbon up and down across the printing 85 point when the types are struck.

From the foregoing, it will be noted that the platen is locked directly to the carriage in both upper and lower position. It will be noted that the platen, at both ends thereof, is supported by and attached to the carriage by means of thrust rods 12, and eccentrics 14, so that vibration or displacement of the platen on the carriage is positively prevented. 90

The structure shown may obviously be modified within the scope of the invention, and portions of the improvements may be used without others. 95

Having thus described my invention, I claim: 100

1. In a typewriting machine, the combination of a platen and a platen frame, a carriage in which the platen frame is shiftable from one case position to another, means on 105 said carriage for locking the platen frame to the carriage in either position, and a key at the keyboard connected to said locking means.

2. In a typewriting machine, a carriage, a platen and a platen frame movable in the carriage between lower and upper case printing positions, means for supporting the platen frame at both ends from the carriage frame, means on said carriage for 110 moving and locking said supporting means to secure the platen in either printing position, and a key at the keyboard connected to said locking means. 115

3. In a typewriting machine, the combination of a platen and a platen frame, a carriage in which the platen frame is shiftable from one case position to another, and eccentrics mounted in the carriage and attached to the platen frame, whereby the platen 125 frame is always supported from the carriage by means of the eccentrics. 120

4. In a typewriting machine, the combination of a platen and a platen frame, a carriage in which the platen frame is shiftable 130

from one case position to another, and eccentrics mounted in the carriage and attached to the platen frame, whereby the platen frame is always supported from the carriage by means of the eccentrics, the eccentrics being at dead center in printing position so that the support of the platen frame in such position is rigid.

5. In a typewriting machine, a carriage, a platen and platen frame movable in the carriage between lower and upper case printing position, means for normally preventing all other movement of the platen frame with respect to the carriage than the movement aforesaid, means on said carriage for locking the platen frame to the carriage in each of said printing positions, and a key at the keyboard connected to said locking means.

10 6. In a typewriting machine, a carriage, a platen and a platen frame hinged to the carriage, means on said carriage for turning the platen frame pivotally on its hinge between lower and upper case printing positions and for holding the platen frame fixedly to the carriage in either position, and a key at the keyboard connected to said holding means.

15 7. In a typewriting machine, a carriage, a platen, and a platen frame hinged to the carriage, and means for turning the platen frame pivotally on its hinge between lower and upper case printing positions, said means being mounted on the carriage and attached to the platen frame forward of the hinge.

20 8. In a typewriting machine, a carriage, a platen, and a platen frame hinged to the carriage, means for turning the platen frame pivotally on its hinge between lower and upper case printing positions, said means comprising an eccentric having a bearing in the carriage, and an arm carried by said eccentric which is attached to the platen frame.

25 9. In a typewriting machine, a carriage, a platen, a platen frame hinged to the carriage, means for turning the platen frame pivotally on its hinge between the lower and upper case printing positions, said means comprising two eccentrics, one at each end of the carriage and having bearing therein, and an arm carried by each eccentric attached to the platen.

30 10. In a typewriting machine, the combination of a platen and a platen frame, a carriage on which the platen frame is adjustable with the platen between upper and lower case positions, means for positively restricting the movement of the platen frame on the carriage to the movement described, eccentrics mounted on the carriage and attached to the platen frame, and means for turning said eccentrics to shift the platen frame between printing positions.

11. In a typewriting machine, the combination of a platen and a platen frame, a carriage on which the platen frame is adjustable with the platen between upper and lower case positions, means for positively 70 restricting the movement of the platen frame on the carriage to the movement described, eccentrics mounted on the carriage and attached to the platen frame, and means for turning said eccentrics to shift 75 the platen frame between printing positions, said eccentrics being on dead center in printing position to lock the platen to the carriage.

12. In a typewriting machine, a carriage, a platen frame hinged thereto, an eccentric shaft having a bearing on the carriage at each end thereof, an eccentric fast to the eccentric shaft at each end thereof, a thrust rod carried by each eccentric and attached 85 to the platen frame, and means for turning said eccentric shaft to move the platen frame on its hinge in the carriage.

13. In a typewriting machine, a carriage, a platen frame hinged thereto, an eccentric 90 shaft having a bearing on the carriage at each end thereof, an eccentric fast to the eccentric shaft at each end thereof, a thrust rod carried by each eccentric and attached to the platen frame, means for turning said 95 eccentric shaft to move the platen frame on its hinge in the carriage, and means for locking the platen frame to the carriage in each shifted position.

14. In a typewriting machine, a carriage, a platen frame movable therein between lower and upper case printing positions, and a plurality of elements coöperating to move the platen frame in the carriage, one of said elements being a key-operated lever, 105 and another of said elements being a two-armed lever, one arm of which is engaged by the first lever to actuate the mechanism, and the other arm of which is engaged by the first lever after a pre-determined movement thereof to stop the mechanism. 110

15. In a typewriting machine, a carriage, a platen frame movable therein between lower and upper case printing positions, a plurality of elements coöperating to move 115 the platen frame in the carriage, one of said elements also serving as a stop to another of said elements to determine one of the printing positions of the platen, and means for adjusting the relation of said 120 elements to determine the stopping position of the same.

16. In a typewriting machine, a carriage, a platen frame movable therein between lower and upper case printing positions, a plurality of elements coöperating to move 125 the platen frame in the carriage, one of said elements being a key-operated lever, and another of said elements being a two-armed lever, one arm of which is engaged by the 130

first lever to actuate the mechanism, and the other arm of which is engaged by the first lever after a pre-determined movement thereof to stop the mechanism, and means 5 for adjusting the effective length of said stopping arm to determine the stopping position of the mechanism.

17. In a typewriting machine, a carriage, a platen frame movable therein between 10 lower and upper case printing positions, a plurality of elements coöoperating to move the platen frame in the carriage, one of said elements being a key-operated lever, and another of said elements being a two-armed 15 lever, one arm of which is engaged by the first lever to actuate the mechanism, and the other arm of which is engaged by the first lever after a pre-determined movement thereof to stop the mechanism, the points 20 of engagement of said first lever with said two-armed lever being on opposite sides of the pivot of said two-armed lever, whereby said pivot acts as a positive stop to receive the blow of the key lever.

25 18. In a typewriting machine, a carriage, a platen frame movable therein, means for moving the platen frame, consisting of an eccentric shaft having a bearing at each end in the carriage and having an eccentric at 30 each end on which eccentrics the platen frame is carried, and an element keyed to the eccentric shaft for turning the shaft, the keyway in the shaft extending substantially the length of the shaft whereby the shaft 35 may be fed longitudinally with the carriage while the element which is keyed thereto is held stationary.

19. In a typewriting machine, a carriage, a platen frame movable therein, means for 40 moving the platen frame, consisting of an eccentric shaft having a bearing at each end in the carriage and having an eccentric at each end on which eccentrics the platen frame is carried, an element keyed to the 45 eccentric shaft for turning the shaft, the keyway in the shaft extending substantially the length of the shaft whereby the shaft may be fed longitudinally with the carriage, while the element which is keyed thereto is 50 held stationary, a rock shaft on the frame of the machine geared to said element on the eccentric shaft, and means for turning the rock shaft from a suitable key.

20. In a typewriting machine, a carriage, 55 a platen frame movable therein, means for moving the platen frame, consisting of an eccentric shaft having a bearing at each end in the carriage and having an eccentric at each end on which eccentrics the platen is 60 carried, an element keyed to the eccentric shaft for turning the shaft, the keyway in the shaft extending substantially the length of the shaft whereby the shaft may be fed longitudinally with the carriage while the 65 element which is keyed thereto is held sta-

tionary, and a rock shaft on the frame of the machine geared to said element on the eccentric shaft and engaging the said element to hold the same against longitudinal movement with the carriage.

21. In a typewriting machine, a carriage, a platen frame movable therein, means for moving the platen frame, consisting of an eccentric shaft having a bearing at each end in the carriage and having an eccentric at each end on which eccentrics the platen frame is carried, an element keyed to the eccentric shaft for turning the shaft, the keyway in the shaft extending substantially the length of the shaft whereby the shaft may be fed longitudinally with the carriage while the element which is keyed thereto is held stationary, a rock shaft on the frame of the machine geared to said element on the eccentric shaft and having an arm fast thereto, and a key-operated lever pivoted on the frame of the machine for engaging said arm on the rock shaft to turn the latter.

22. In a typewriting machine, a carriage, a platen frame movable therein, means for moving the platen frame, consisting of an eccentric shaft having a bearing at each end on the carriage, and having an eccentric at each end on which eccentrics the platen frame is carried, an element keyed to the eccentric shaft for turning the shaft, the keyway in the shaft extending substantially the length of the shaft whereby the shaft may be fed longitudinally with the carriage, while the element which is keyed thereto is held stationary, a rock shaft on the frame of the machine geared to said element on the eccentric shaft and having an arm fast thereto, a key-operated lever pivoted on the frame of the machine for engaging said arm on the rock shaft to turn the latter, and a stop carried by said rock shaft for determining the movement of the same by the key-operated lever.

23. In a typewriting machine, a carriage, a platen frame movable therein, means for moving the platen frame, consisting of an eccentric shaft having a bearing at each end on the carriage, and having an eccentric at each end on which eccentrics the platen frame is carried, an element keyed to the eccentric shaft for turning the shaft, the keyway in the shaft extending substantially the length of the shaft whereby the shaft may be fed longitudinally with the carriage, while the element which is keyed thereto is held stationary, a rock shaft on the frame of the machine geared to said element on the eccentric shaft and having an arm fast thereto, a key-operated lever pivoted on the frame of the machine for engaging said arm on the rock shaft to turn the latter, and a stop carried by said rock shaft and engaged by said key-operated lever to determine the movement of the parts.

24. In a typewriting machine, a carriage, a platen frame movable therein, means for moving the platen frame, consisting of an eccentric shaft having a bearing at each end on the carriage and having an eccentric at each end on which eccentrics the platen frame is carried, an element keyed to the eccentric shaft for turning the shaft, the keyway in the shaft extending substantially the length of the shaft whereby the shaft 5 may be fed longitudinally with the carriage, while the element which is keyed thereto is held stationary, a rock shaft on the frame of the machine geared to said element on the eccentric shaft and having an arm fast thereto, a key-operated lever pivoted on the frame of the machine for engaging said arm on the rock shaft to turn the latter, and a stop carried by said arm on the rock shaft 10 and engaged by said key-operated lever to determine the movement of the parts.

25. In a typewriting machine, a carriage, a platen frame movable therein, means for moving the platen frame, consisting of an eccentric shaft having a bearing at each end on the carriage, and having an eccentric at each end on which eccentrics the platen frame is carried, an element keyed to the eccentric shaft for turning the shaft, the key- 25 way in the shaft extending substantially the length of the shaft whereby the shaft may be fed longitudinally with the carriage, while the element which is keyed thereto is held stationary, a rock shaft on the frame of the machine geared to said element on the eccentric shaft and having an arm fast thereto, a key-operated lever pivoted on the frame of the machine for engaging said arm on the rock shaft to turn the latter, and a 30 stop adjustable on said arm on the rock shaft and engaged by said key-operated lever to determine the movement of the parts.

26. In a typewriting machine, a carriage, a platen frame movable therein between lower and upper case printing position, means for so moving the platen frame, comprising a rock shaft on the frame of the machine suitably geared to the platen frame, a key-operated lever, means whereby said 45 lever is caused to turn the rock shaft, and a stop carried by said rock shaft engaged by said key-operated lever to determine the movement of the parts.

27. In a typewriting machine, a ribbon carrier, a carriage, a platen frame movable therein between lower and upper case printing positions, a rock shaft mounted on the frame of the machine and geared to the platen to move the latter, a key-operated 50 lever, means whereby the shaft is rocked by said lever, means operated from said rock shaft for moving the ribbon carrier with the platen from one to the other printing position, said last named means comprising 55 a rack attached to the ribbon carrier, and

a toothed element on the rock shaft engaging therewith.

28. In a typewriting machine, the combination with a carriage, of a platen frame mounted thereon for shifting movement, a 70 rock shaft extending from end to end of the carriage, eccentrics on the ends of said rock shaft, links pivoted on said eccentrics and connected to the platen frame to shift the same, and means for turning said rock 75 shaft sufficiently to shift the platen back and forth and lock it in each position.

29. In a typewriting machine, the combination with a carriage, of a platen frame mounted thereon for shifting movement, a 80 rock shaft extending from end to end of the carriage, eccentrics on the ends of said rock shaft, links pivoted on said eccentrics and connected to the platen frame to shift the same, means for turning said rock shaft 85 sufficiently to shift the platen back and forth and lock it in each position, a pinion splined to said rock shaft, a gear mounted on the frame of said machine and meshing with said pinion, and a key connected to said 90 gear, means being provided to prevent movement of the pinion in axial direction.

30. In a typewriting machine, the combination with a carriage, of a platen frame mounted thereon for shifting movement, a 95 rock shaft extending from end to end of the carriage, eccentrics on the ends of said rock shaft, links pivoted on said eccentrics and connected to the platen frame to shift the same, means for turning said rock shaft sufficiently to shift the platen back and forth and lock it in each position, and a ribbon-controlling mechanism including a member 100 connected to said turning means to be shifted in accordance with the movement of the 105 platen.

31. In a typewriting machine, the combination with a carriage, of a platen frame mounted thereon for shifting movement, a 110 rock shaft extending from end to end of the carriage, eccentrics on the ends of said rock shaft, links pivoted on said eccentrics and connected to the platen frame to shift the same, and means for turning said rock shaft sufficiently to shift the platen back and forth 115 and lock it in each position, including a member splined to accommodate the movement of the carriage.

32. In a typewriting machine, the combination with a carriage, of a platen frame 120 mounted thereon for shifting movement, a rock shaft extending from end to end of the carriage, eccentrics on the ends of said rock shaft, links pivoted on said eccentrics and connected to the platen frame to shift the 125 same, means for turning said rock shaft sufficiently to shift the platen back and forth and lock it in each position, including a member splined to accommodate the movement of the carriage, and a ribbon-control- 130

ling mechanism including a member connected to said turning means to be shifted in accordance with the movement of the platen.

33. The combination of a carriage, a platen frame shiftable on said carriage, mechanism mounted on said carriage and movable with relation to both said carriage and said platen frame, for shifting the latter, a key at the keyboard of the machine, means controlled by said key for operating said shifting mechanism, and including a device for accommodating the traveling movement of the carriage, a ribbon-controlling mechanism supported on the framework of the machine, and means extending from said key to said ribbon-controlling mechanism to shift the latter in accordance with the shifting of the platen.

34. The combination of a carriage, a platen frame shiftable on said carriage, mechanism mounted on said carriage and movable with relation to both said carriage and said platen frame, for shifting the latter, a key at the keyboard of the machine, and means controlled by said key for operating said shifting mechanism, and including a device for accommodating the traveling movement of the carriage; said platen-shifting mechanism including an eccentric device on said carriage and means coöperating therewith to lock the platen in each of its shifted positions.

35. The combination of a carriage, a platen frame shiftable on said carriage, mechanism mounted on said carriage and movable with relation to both said carriage and said platen frame, for shifting the latter, a key at the keyboard of the machine, means controlled by said key for operating said shifting mechanism, and including a device for accommodating the traveling movement of the carriage, said platen shifting mechanism including eccentrics, one at each end of the platen frame, a rock shaft rigidly connecting said eccentrics, and means coöperating with said eccentrics to shift the platen and lock it in each of its shifted positions.

36. The combination of a carriage, a platen shiftable thereon, means between the carriage and the platen and movable relatively to both thereof for shifting the platen, a key, a rock-shaft on the framework of the machine and connected to said key, means between said rock-shaft and said shifting means for operating the latter, provision being made for accommodating the travel of the carriage, a pinion on said rock shaft, a rack meshing with said pinion, and a ribbon vibrating device mounted on said rack to be shifted in accordance with the shifting of the platen.

37. The combination of a carriage, a shiftable platen thereon, a key-operated rocking

member, means between said rocking member and said platen for shifting the latter, a device on said rocking member, a part engaged by said device to be shifted thereby, and a ribbon-vibrating member mounted on said part to be shifted in accordance with the shifting of the platen.

38. In a typewriting machine, the combination of a platen, a platen frame, a carriage, and a set of eccentrics and links connecting said platen frame to said carriage to shift the platen frame and lock the same to the carriage.

39. In a typewriting machine, the combination of a platen, a platen frame, a carriage, and a set of eccentrics and links connecting said platen frame to said carriage to shift the platen frame and lock the same to the carriage in either position to which the platen is shifted thereby; and a key upon the framework of the machine connected to said set of eccentrics and links; provision being made to accommodate the travel of the carriage.

40. The combination of two primary elements consisting of a carriage and a platen frame, a rock-shaft mounted on one of said primary elements and connected to the other to shift said platen frame with relation to said carriage, and a key mounted on the framework of the machine and connected to said rock shaft to operate the same, means being provided to accommodate the traveling movement of the carriage.

41. The combination of two primary elements consisting of a carriage and a platen frame, a rock-shaft mounted on one of said primary elements and connected to the other to shift said platen frame with relation to said carriage, an operating device splined on said rock shaft, means to prevent said operating device from traveling with the carriage, and a key connected to said operating device.

42. The combination of two primary elements consisting of a carriage and a platen frame, a rock shaft mounted on one of said elements, eccentrics on said rock shaft, connections from said eccentrics to the other of said primary elements to shift the platen and lock it in each of its shifted positions, an operating device splined on said rock shaft, means to prevent said operating device from traveling with the carriage, and a key connected to said operating device.

43. The combination of two primary elements consisting of a carriage and a platen frame, a rock shaft mounted on one of said elements, eccentrics on said rock shaft, connections from said eccentrics to the other of said primary elements to shift the platen and lock it in each of its shifted positions, pinion splined on said rock shaft, means to prevent said pinion from traveling with the

carriage, a toothed element meshing with said pinion, and a key to operate said toothed element.

44. The combination of two primary elements consisting of a carriage and a platen frame, a rock shaft mounted on one of said elements, eccentrics on said rock shaft, connections from said eccentrics to the other of said primary elements to shift the platen 10 and lock it in each of its shifted positions,

an operating device splined on said rock shaft, means to prevent said operating device from traveling with the carriage, a key connected to said operating device, and a ribbon-vibrator also connected to said key 15 to be shifted with the platen.
